UNITED STATES PATENT OFFICE.

ERNST SAUER, OF SCHLOSS KAIBITZ, NEAR KEMNATH, GERMANY.

PROCESS OF PRODUCING INTAGLIO-PRINTING FORMS.

Application filed February 3, 1921, Serial No. 442,284. Renewed June 22, 1923.

(GRANTED UNDER THE PROVISIONS OF THE ACT OF MARCH 3, 1921, 41 STAT. L. 1313.)

To all whom it may concern:

Be it known that I, ERNST SAUER, a citizen of Germany, residing at Schloss Kaibitz, near Kemnath, Bavaria, Republic of Germany, have invented new and useful Improvements in and Processes of Producing Intaglio-Printing Forms (for which I have filed applications in Germany Patent No. 340003, Aug. 24, 1919; Luxemburg No. 11606, 10 Jan. 21, 1920; Switzerland No. 86,573 Jan. 19, 1920; Spain No. 72356 June 22, 1920; France No. 509434 Feb. 5, 1920; England No. 156420 Jan. 30, 1920; Norway No. 32312 Feb. 7, 1920; Denmark No. 27863 June 11, 1921; 15 Sweden No. 49798 Feb. 8, 1920; Belgium No. 284982 Feb. 11, 1920; Hungary No. 78196 Jan. 21, 1920), of which the following is a specification.

This invention relates to intaglio-printing forms and a process of producing them in a photo-mechanical way and its object is to give such forms any required depth by means of a peculiar manner of copying without manual labor and to prevent that the 20 ink being extracted from the recesses of the inked form by the scraper for removing the excess of ink. With this end in view the process is carried out in the following manner illustrated in the accompanying drawing, in which:

Fig. 1 a cross-section through a transparent carrier with a layer of bichromated gelatine at one side,

Fig. 2 a cross-section through the same carrier with a screen-plate applied to its bichromated layer,

Fig. 3 a screen-plate in plan,

Fig. 4 is a cross section through the bichromated gelatin coated carrier after exposure through the screen, which has been removed and with a diapositive applied to the reverse side of the carrier and after exposure through said diapositive, and

Fig. 5 is a cross section through the transparent carrier and its bichromated gelatin after exposure and development.

A plate *a*, Fig. 1, of a more or less transparent material, such as celluloid, acetyl-cellulose (cellon), paper or the like is at one side covered with a layer *b* of a thickness of 0,06 to 0,08 mm. of bichromated-gelatine in such a manner that the gelatine firmly adheres to its carrier *a*. The screen-plate *c*, Figs. 2 and 3, (having transparent

lines and opaque dots) is then applied to the bichromated-gelatine layer *b* and is exposed to the light until the lines of the screen *c* appear as tanned lines in the layer of gelatine *b*, see wedges *d*, Figs. 2, 4 and 5, which in bright sunshine requires an exposure of about 3½ to 4 minutes. Now the screen *c* is removed and a diapositive *e* of the picture to be reproduced is applied to the reverse side of the carrier and the bichromated gelatin layer *b* is exposed to light passing through the diapositive *e* and the carrier *b* to the bichromated gelatine *b*, so that this portion of it is completely tanned up to the surface of the layer, see *h*, *i*, *k*, *l*, Figs. 4 and 5. The less transparent places of the diapositive allow only so much light to pass that the bichromated-gelatine layer is only tanned to a certain depth and as below the opaque parts *m* and *n* of the dia-positive *e* the bichromated gelatine layer is not tanned by the exposure, on developing the plate by means of warm water the following result will be observed:

The face of the printing form is level in so far as the bars *d*, *d*, Figs. 2, 4 and 5, of the screen remain of equal depth throughout the whole picture. On the other hand the exposure from the back of the printing plate forms a relief which corresponds exactly with the picture, so that at the parts of the picture where less light has penetrated recesses are formed between the bars of the screen, which recesses are intended to hold the ink. The bars of the screen are at the surface of the bichromated-gelatine layer *b* of the same width as the lines of the screen, while they are thinner in the depth of the layer of gelatine, which is due to the fact that the light during the copying of the screen cannot act so intensely at lower depths of the layer of gelatine. These extremely fine bars in the depth of the layer of gelatine are strengthened at the bottom of the layer by exposure through the dia-positive from the back of the printing plate so that they do not break down during the developing process. In consequence of the fact that the bars of the screen are thinner at the back than at the front of the printing plate, recesses are formed between the bars of the screen which at the back are wider than at the front. The undercut walls of the recesses will naturally hold the ink con-

tained in the recesses more safely than bars of uniform thickness and the ink will not be drawn out of the recesses when the printing form is scraped. In order to render the printing form and the face of the layer of gelatine consisting of the intersecting bars of the screen better capable of resisting the ink scraper, it is preferably lightly moistened with acetic acid and then coated with 10 a suitable varnish, such as zapon-varnish.

What I claim as my invention and desire to secure by United States Letters Patent is:—

1. The process of producing intaglio-printing forms, which consists in coating a transparent carrier with a layer of bi-chromated-gelatine, applying an intaglio screen-plate to the face of said layer, exposing to the light through said screen, applying a dia-positive of the picture to the uncovered side of said carrier and exposing to the light through said dia-positive and developing by means of warm water.

2. As a new article of manufacture an intaglio-printing form comprising a carrier plate having a level screen on one face and a relief of the picture to be reproduced between the bars of said screen, the said screen and the said relief consisting of tanned bi-chromated-gelatine. 25

3. As a new article of manufacture an intaglio-printing form comprising a carrier plate having a level screen on one face, the bars of said screen being undercut and a relief of the picture to be reproduced between the said bars of said screen, the said screen and the said relief consisting of tanned bi-chromated-gelatine. 30

In testimony whereof I have signed my name to this specification in the presence of 40 two subscribing witnesses.

ERNST SAUER.
